UNITED STATES PATENT OFFICE.

HELEN L. GERAGHTY, OF ISHPEMING, MICHIGAN, ASSIGNOR OF ONE-THIRD TO OSCAR J. LIDBERG, OF GRAND RAPIDS, MINNESOTA.

COMBINED CAP AND HAND-BAG.

1,269,594.

Specification of Letters Patent. Patented June 18, 1918.

Application filed April 3, 1917. Serial No. 159,515.

To all whom it may concern:

Be it known that I, HELEN L. GERAGHTY, a citizen of the United States, residing at Ishpeming, in the county of Marquette and 5 State of Michigan, have invented certain new and useful Improvements in Combined Caps and Hand-Bags, of which the following is a specification.

This invention relates to convertible head gear and has as its primary object to provide an article of this class which may be utilized either as an automobile cap or as a hand bag and which will be readily convertible for either use. 10 15 It is also an aim of the invention to provide an article of the class above mentioned which will possess a neat and attractive appearance when worn as a cap and yet will have a maximum capacity when employed as 20 a hand bag.

A further aim of the invention is to provide, in an article of the class mentioned, members designed to serve as draw strings, and wrist straps when the article is employed as a hand bag, and as chin straps when the article is employed as a cap, these members serving also in this latter use of the article as a means for adapting the cap to the head and causing the rim thereof to 30 more or less snugly fit the head.

Another aim of the invention is to provide an article of this class which may be manufactured from rectangular pieces of cloth, thereby avoiding all waste of material. 35

In the accompanying drawings:

Figure 1 is a view illustrating the manner in which the article embodying the present invention is to be employed as a cap; 40 Fig. 2 is a similar view illustrating the manner in which the same is to be employed as a hand bag;

Fig. 3 is a side elevation of the article in condition for use as a cap, the front and 45 rear flaps thereof being folded down, however, to better illustrate the manner in which the article is formed;

Fig. 4 is a perspective view illustrating the members which serve to restrict the 50 opening of the article and as wrist and chain straps;

Fig. 5 is a plan view of the blank from which the body of the article is formed;

Fig. 6 is a similar view illustrating the 55 blank from which one of the flaps is formed;

Fig. 7 is a detail vertical sectional view through one side of the article when arranged for use as a cap.

The article embodying the present invention includes a body member and front and rear flaps which are united to the margin of the body member and which are provided with hems to receive the members which serve as draw strings and wrist and chin straps and the said body member is indicated in general by the numeral 1 and is formed from a rectangular blank such as shown in Fig. 5 of the drawings, the said body member constituting the crown when the article is employed as a cap and serving as the bag or receptacle proper when the article is employed as a hand bag. As stated, the blank shown in Fig. 5 is rectangular in outline and in forming the body 1 the blank is folded along the lines *a* and *b* 60 to form a more or less well defined box plait 2. The blank is then folded along the diagonal lines *c* which extend diagonally inwardly from the corners of the blank, as shown in Fig. 5, the inner ends of the fold lines *c* at opposite sides of the plait 2 meeting and terminating relatively close to the adjacent fold lines *b*. The blank is also folded inwardly 65 along the parts of the line *d* in Fig. 5 extending toward the edges from the intersections of lines *c*, which line *d* extends from end to end of the blank midway between the fold line *c* at opposite sides of the blank and through the meeting points of these 70 lines and transversely of the box plait 2. 75 Thus at each side of the box plait and between the fold lines *b* and *d* there are formed two approximately triangular two-ply wings, the upper edges of each of which is defined by the respective fold line *c* and the 80 lower edges of each of which is defined by the registering edges of the blank at the opposite sides of each fold line *c*. Each of these wings is then folded back in the direction of the fold line *d* along lines *e*, and 85 then along lines *f* registering with the fold line *d*, so that the wings are folded back upon themselves along the lines *f* and have their lower corners disposed beneath the adjacent sides of the adjacent box plait 2. 90 In thus folding the blank the body will be 95 caused to assume a general hollow dome shape and by reason of the several folds and the presence of the box plait, will possess a fullness permitting of its expansion to adapt 100 105 110

it to perform the function of a cap crown without interfering with the arrangement of the hair. Furthermore, the entire margin of the blank when thus folded will lie on a straight line as will be apparent by reference to Fig. 3 of the drawings.

The flaps of the article, indicated by the numeral 3, are each formed from a blank such as shown in Fig. 6 of the drawings and 10 this blank is rectangular and is folded longitudinally medially along the line *g*. The blank is also folded along the lines *h*, parallel to each longitudinal edge of the blank, to form hems 4 and these edges of the blank 15 are disposed against the inner and outer faces of the marginal portion of the body 1, as clearly shown in Fig. 7 of the drawings, and are united thereto by a line of stitching 5. The said edge portions of the flap 3 may 20 be further united to the marginal portion of the body 1 by a line of stitching 6 extending parallel to the line of stitching 5. A line of stitching 7 is also passed through the spaced portions or folds. Thus between the lines 25 of stitching 6 and 7 in each flap there is formed a pocket or hem 8 in which the draw members heretofore referred to are housed. It will be understood at this point that the lines of stitching 5 and 6 serve not only 30 to unite the flaps to the body of the article but also to secure the triangular wings heretofore referred to in their folded condition and thereby prevent expansion of the rim of the body 1 beyond a certain limit although 35 not in any way interfering with the expansion of the body proper in taking advantage of the fullness provided by the several folds therein heretofore described. By reference to Figs. 1, 2 and 3 of the drawings it 40 will be observed that the ends of the flap 3 meet each other at the opposite sides of the article without, however, being united, so that the pocket or hem 8 in each flap is open at both ends to permit of the passage there- 45 through of the draw members heretofore referred to.

There are two of the above-mentioned draw members provided each of which comprises a cord 9 which is looped and has the 50 sides of its loop loosely threaded through the hems 8 in the two flaps 3, the loops being threaded through in opposite directions, or, in other words, being oppositely disposed so that the end of one loop will extend beyond

one side of the article and the end of the 55 other loop will extend beyond the other side of the article. It will now be understood that when the projecting ends of the loops are pulled in opposite directions, or, in other words, outwardly from the article, the opening or mouth of the article will be contracted and thus when the article is employed as a hand bag the members 9 will serve as draw strings and the projecting ends thereof will serve as wrist loops. When the article is 60 employed as a cap and is applied to the head, the projecting ends of the loops 9 are brought beneath the chin, as shown in Fig. 1 of the drawings, and connected together preferably by the engagement of a button 65 10 upon one loop within the extended end of the other loop. Of course, in drawing the loops beneath the chin the loops will serve in the manner of draw strings and will cause the rim of the crown or body member 1 to 70 15 more or less snugly fit the head.

It will further be observed by reference to Fig. 6 that the blank shown in this figure is to be folded along lines *i* parallel to each end edge so that the ends of the flaps 3 will 75 80 present a neat appearance.

Having thus described the invention, what is claimed as new is:—

1. In an article of the class described, a body member having a box seam extending 85 transversely thereof and further provided with wings located at the opposite sides of the box seam and having their lower edges lying in the rim line of the body member, the folds forming the wings being closed at 90 said rim line of the body.

2. In an article of the class described, a body or crown member having a box plait extending transversely thereof, the body at each side of the box plait being formed with 95 two ply wings, the plies of the wings being mutually disconnected except at their line of juncture and at their lower edges where they are secured to each other and to the lower edges of the sides of the body member, and a 100 hem member having plies secured to the inner and outer faces of the sides, front and back of the body member and receiving and binding the said lower edges of the body member. 105

In testimony whereof I affix my signature.

HELEN L. GERAGHTY. [L.S.]
